UNITED STATES PATENT OFFICE.

THEODORE HUBERT, OF CRANFORD, AND CHARLES E. LOCKWOOD, OF PLAINFIELD, NEW JERSEY; SAID HUBERT ASSIGNEE, BY MESNE ASSIGNMENTS, TO AMERICAN CIRCULAR LOOM COMPANY, OF PORTLAND, MAINE, A CORPORATION OF MAINE.

ELECTRIC IGNITION SYSTEM.

1,090,917.

Specification of Letters Patent. Patented Mar. 24, 1914.

Application filed August 5, 1909. Serial No. 511,418.

To all whom it may concern:

Be it known that we, THEODORE HUBERT and CHARLES E. Lockwood, citizens of the United States, and residents of Cranford and Plainfield, respectively, in the county of Union and State of New Jersey, have invented certain new and useful Improvements in Electric Ignition Systems, of which the following is a specification.

10 In some ignition systems for gas engines a battery and a magneto or dynamo operate through the primary coil of the same transformer, and spark plugs are maintained in the circuit of the secondary of the transformer. When the switch in the battery circuit is opened a discharge in the primary of the transformer occurs, and sparks will jump at the plugs. This is liable to occur at a time when the pistons of one or more 20 cylinders are not in proper position to receive the resulting explosion of gas in the cylinders, hence there is danger of injury to parts of the engine.

The object of our invention is to provide 25 means to prevent sparks from jumping at the plugs at the moment of such break in the battery circuit, and to this end we provide means, operated upon turning the switch, to short circuit or break the circuit of the 30 secondary of the transformer.

Our invention also comprises novel details of improvement that will be more fully hereinafter set forth and then pointed out in the claims.

35 Reference is to be had to the accompanying drawings forming part hereof, wherein— Figure 1 is a diagrammatic view of an ignition system embodying our improvements. Fig. 2 is a face view of the switch, 40 looking from the opposite side of Fig. 1. Fig. 3 is an edge view of the switch, partly in section, and Fig. 4 is a diagrammatic view of a modification.

At 1 is indicated generally a suitable 45 switch, shown provided with contacts 2, 3, for connection with the lines 4, 5, of the circuit of battery 6, and with contacts 7, 8, for connection with the conductors 7^a, 8^a, of a magneto or dynamo. The switch member 50 or contact 9 connected with the button or handle 10 is adapted to close the circuit between contacts 2, 3, and 7, 8, respectively, to include the battery or the other generator in the circuit. The conductor 4^a of the bat-

tery circuit leads to the primary winding 11 of the transformer. The circuit of the battery, as well as that of the other generator, is opened and closed by a timer in any usual or suitable manner. As shown, conductor 4^b leading from winding 11 is connected with a movable contact 12 adapted to engage a contact 13 in circuit with battery wire 5, and a rotative arm 14 acting upon lever 15 that carries contact 12 serves to make and break the circuit at the proper time at contacts 12, 13. The secondary winding 11^a of the transformer is in circuit with the spark plugs 16.

As so far described, the parts may be of usual or suitable construction adapted for ignition systems of gas engines.

At 17, 18, are contacts associated with the terminals of the corresponding secondary winding 11^a of the transformer, and at 19 is indicated a spark gap connected with the 75 terminals of the corresponding secondary winding 11^a. In Fig. 1 the contacts 17, 18, are connected directly to the terminals of secondary winding 11^a, while in Fig. 4 the contacts 17, 18, are in the same side of the 80 circuit of the secondary winding.

At 20 is a contact adapted to engage the corresponding contact 17, 18, and arranged either to short circuit winding 11^a, as in Fig. 1, before contact 9 leaves contact 2, when the 85 break in the battery circuit occurs or to break the circuit of winding 11^a before such break occurs in the circuit of the battery, as in Fig. 4.

At 21 is a rotative member or cam operated by key 10 coincidental with the operation of contact 9, for which purpose member 21 may be suitably connected with or formed integrally with the stem 1^a of switch 1. Member 21 is shown provided with a projection 21^a adapted to operate contact 20, said contact being shown carried by an arm 20^a pivotally supported at 22 upon the part 23 that carries the switch (which may be the box that contains the transformer), and arm 20^a is shown normally maintained in proper position with respect to member 21 by spring 24. Arm 20^a is shown provided with a projection 20^b to be engaged by projection 21^a of member 21 for rocking arm 105 20^a.

With reference to Figs. 1, 2 and 3, the relative arrangement of parts is such that

when contact 9 engages contacts 2 and 3 the contact 20 will be out of engagement with contacts 17 and 18, and current from the battery may flow through transformer 11 as usual, but when contact 9 is turned (to the left in Fig. 1) and just as it leaves contact 2 or 3, the projection 21^a, acting upon projection 20^b, will have moved arm 20^a to cause contact 20 to engage contacts 17 and 18 to short circuit coil 11, so that when a discharge occurs in coil 11 at the break between contacts 9 and 2 or 3 the induced current caused by the break of the battery circuit will, by reason of such short circuit, prevent sparks from jumping at the spark plugs. When contact 9 moves farther to the left to engage contacts 7 and 8 the projection 21^a will leave projection 20^b and permit contact 20 to break the circuit at contacts 17, 18, for proper operation of the other generator circuit to produce sparks at the spark plugs.

The foregoing description applies to one of the arms 20^a, as at the left in Fig. 1, but similar action occurs with respect to contacts 17, 18 and 20 at the right of Fig. 1, viz: Just as contact 9 leaves contact 2 or 3, the projection 21^a at the right engaging the adjacent end of arm 20^a, moves its contact 20 into engagement with contacts 17 and 18 to short circuit the coil 11 at the right to prevent sparks jumping at the corresponding spark plugs, and when contact 9 moves farther to the left to engage contact 7 and 8 the aforesaid projection 21^a will leave the adjacent projection of arm 20^a and permit the corresponding contact 20 to break the circuit at contacts 17, 18 at the right, as described with respect to the parts at the left. In other words, both arms 20^a are operated simultaneously during the rotation of contact 9. This applies to the illustration of Fig. 1 adapted for a four cylinder engine, but if the system is installed in a two cylinder engine, then but one-half of the devices described will be used. When switch 9 is again turned back toward contacts 2, 3, the projection 21^a will ride under projection 20^b to restore the parts to the normal positions shown in Fig. 1 in full lines.

In Fig. 4 the parts are so arranged that when contact 9 engages contacts 2, 3, or 7 and 8, the contact 20 will be in engagement with contacts 17 and 18 to close the corresponding circuit of secondary winding 11^a. In this case contact 20 is insulated from arm 20^a, as by suitable insulation 20^c, and when contact 9 moves away from contacts 2, 3, the projection 21^a acting upon projection 20^b will move contact 20 away from contacts 17, 18, as in dotted lines in Fig. 4, and when member 21 has been turned sufficiently far the projection 21^a will release projection 20^b and contact 20 will

move back to contacts 17 and 18 for closing the circuit of the secondary winding when contact 9 engages contacts 7 and 8. On the reverse movement of contact 9 the parts will be restored to their proper positions.

While in Figs. 1 and 4 we have shown two transformers, four spark plugs (one for each cylinder) and two arms 20^a operated by two projections from member 21, which is designed for a four cylinder gas engine, it will be understood that for a two cylinder gas engine one of the arms 20^a and the corresponding transformer, etc., need not be used, and that for an engine having more than four cylinders the circuits will be correspondingly arranged in well known manner.

The timer shown in Figs. 1 and 4 may be utilized in conjunction with the arrangements set forth, for a four-cylinder engine, in manner substantially the same as set forth in Letters Patent No. 1,064,329 granted to T. Hubert, June 10, 1913.

Having now described our invention what we claim is:

1. An electric ignition system comprising a generator circuit including a transformer, a switch to control said circuit, and means controlled by said switch for preventing the discharge from the secondary winding of the transformer through the ignition circuit upon breaking said generator circuit.

2. An electric ignition system comprising a circuit including a generator and a transformer, spark plugs in the circuit of the secondary of the transformer, contacts associated with the secondary of the transformer, a contact to open and close the circuit at the first named contacts, a switch for the first named circuit, and means controlled by said switch for operating the second named contact to make and break the circuit through said first named contacts upon a break in the circuit by said switch.

3. An electric ignition system comprising a circuit including a generator and a transformer, a switch to control said circuit, an arm, means to operate said arm by said switch, a contact controlled by said arm, and contacts associated with the secondary winding of the transformer to co-act with the first named contact.

4. An electric ignition system comprising a circuit including a generator and a transformer, a switch to control said circuit, spark plugs connected with the secondary of the transformer, and means controlled by said switch for short circuiting the transformer secondary winding upon said generator circuit being broken.

5. An electric ignition system comprising a circuit including a generator and the primary winding of a transformer, a switch to control said circuit, a member operated by

said switch, an arm operated by said member, a contact controlled by said arm, and contacts associated with the secondary winding of said transformer to be engaged by the first named contact for preventing the discharge of current from the secondary winding through the plugs as the circuit of said generator is broken.

6. An electric ignition system comprising a circuit including a generator and the primary winding of a transformer, a switch in said circuit, a member connected with said switch and provided with a projection, a movable arm having a projection to co-act with the first named projection, a contact controlled by said arm, spark plugs and contacts associated with the secondary winding of the transformer, said projections being arranged to maintain the first named contact out of connection with said contacts when said circuit is closed at the switch and to close circuit through said contacts as the first named circuit is broken at the switch and to break circuit through said contacts upon further movement of the switch.

7. The combination of a switch provided

with a movable member and contacts spaced apart to be engaged by the movable member of the switch, one of the aforesaid contacts being connected with a circuit including a battery and the primary winding of a transformer, another of the aforesaid contacts being adapted for connection with the winding of a magneto or dynamo, contacts associated with the secondary winding of said transformer, a movable member operated with the movable member of said switch, and a contact to engage the contacts of said secondary winding and controlled by said member for preventing the discharge from said secondary winding through the ignition circuit upon a break at the switch in the first named circuit.

Signed at New York city, in the county of New York and State of New York, this 2nd day of August, A. D. 1909.

THEODORE HUBERT.
CHARLES E. LOCKWOOD.
